MOP

Max Veeck, West Manayunk, Pa.

Application July 27, 1936, Serial No. 92,700

3 Claims. (Cl. 15—228)

This invention relates to mops, especially to those adapted for dusting and polishing floors, and more particularly this invention relates to the swabs of such mops.

5 In providing a mop for use in dusting floors, walls or ceilings, as well as for polishing floors, one of my objects is to provide a complete mop, having among other things, a strong frame having one end divided into two spaced, longitudinal, 10 portions, adapting the frame to be journaled with the handle, at some mid-point in the frame, so as to permit the frame to swing either way through the plane of the handle. A further object is to provide a suitably fitting swab, adapted 15 to be slipped upon the frame from the end of the handle, having pocket parts to said swab, into which fit the said spaced, frame portions, and having the side body parts of said swab extend beyond the undivided end of the frame, and 20 adapted to be releasably joined, to complete the covering of the frame by the swab. I desire to have a closable opening at the end of the swab body, opposite to the pocket part end, and to have an extension to said body, beyond said opening, adapted to overlap and connect with the upper opposite side of said body to enclose the said 25 mop frame, to insure covering the frame end, to prevent marring furniture, baseboards, etc.

A further object is to provide a mop swab 30 which, while being adapted to fit the said frame, and to fulfill the above named objects, will be provided with a soft sleeve of fabric or other suitable material, either as part of the swab body or separate therefrom, and adapted to fit over the 35 joint of the frame and the handle end, and extend along the said handle between the said pocket parts of the swab, so as to complete the covering of working parts of said frame, with its handle joint, so as not to mar what the mop 40 may come into contact with during its use.

With these and other objects, which will hereinafter appear, my invention resides in certain structures of mop swab and frame which are illustrated in the accompanying drawings, including showing a marking of the sheet fabric used in making the mop swab. The structures of the frames and swabs, as well as the making of the swabs, are described and their functioning and use is explained. What I claim is set forth.

50 In the drawings,

Figure 1 is a perspective view of a mop partly assembled and embodying my invention.

Figure 2 is a perspective view of the sleeve adapted to fit over the journaled end of the handle.

Figure 3 is an elevation of a modified form of swab on the frame and handle, differing from that shown in Figure 1.

Figure 4 is a perspective view of one form of mop frame, journaled upon a handle.

Figure 5 is a perspective view of a mop embodying my invention, shown in a position of use, upon a fragment of floor.

Figure 6 is a sectional elevation of the upper end portion of a mop swab mounted upon a portion of the frame, showing the overlapping of the swab sides on one another.

Figure 7 is a perspective view of a partly put-together swab similar to that shown in Figure 1.

Figure 8 shows in plan view, a lay-out of the 15 swab form, on sheet material, having certain parallel guide lines marked on the material.

Figure 9 shows in plan view a cut out, and partly formed, swab, as the same succeeds in formation from that shown in Figure 8.

Figure 10 is a perspective view of a partly 20 formed side of the sleeve shown in Figures 7 and 9.

Figure 11 shows in plan view a piece of a strip of material on which a different lay-out of form 25 of swab is marked than that shown in Figure 8.

Figure 12 shows in plan view the partly completed swab which is shown laid out in Figure 11.

Figure 13 shows in perspective view the partly completed swab shown in plan, in Figure 12.

In the figures, referring first to Figures 1, 2, 4 and 6, there is shown mounted upon the handle 15, a cap 16, secured thereto by the nail 17. Upon the cap 16 is mounted the frame 18, having its ends 19 and 20, engage holes 21, in the cap 16. 35 As shown in Figure 1, the frame 18, has fixed thereto, a flat portion 22, of sheet metal or other suitable flat material, extending across the area enveloped by the wire frame 18. The flat portion 22 has burred projections 23, on its surface, to keep the swab 28 from slipping thereon. This frame 18 has an end portion 24 terminating in the blunt point 25. The part of the frame 18, opposite to the end portion 24, has two arm portions 26 and 27, so spaced, as to permit the handle 40 45 to swing freely between them.

As shown in Figure 1, the swab 28 partly engages the frame 18, having the said spaced arm portions 26 and 27, entering into the respective pockets 29 and 30, of the swab 28. Shown turned down in Figure 1, is the flap 31, of the body of the swab 28. Back of the flap 31, and behind the frame 18, is shown the flap 32. Each of these flaps 31 and 32 is shaped to fit the pointed end portion 24, of the frame 18. The flap 31 has 50 55

overlap extensions 33 and 34, adapted to overlap the angular end of the portion 24, of the frame 18, when the swab 28 is drawn up to fully cover the frame 18, and these extensions 33 and 34, of the flap 31 are adapted, by their formation, to turn over the end of frame 18 and overlap the other swab flap 32, and by means of the snap fasteners 35, and the tying tapes 36, can there—in their overlapped position—releasably attach the flap 31 to the flap 32, while completely enclosing the end of the frame 18.

Where the cap 16, of the handle 15, is journaled with the frame 18, a sleeve 37 fits over, and extends part away along the handle 15. Side holes 38 are provided in the head of the sleeve 37, to permit the frame ends 19 and 20, to pass within, to engage the cap 16, in journaled relation.

In Figure 3, the sleeve 39 is shown to be part of the body, of the swab 40. Other parts of the swab 40, similar to like parts of the swab 28, are similarly numbered. The frames 18, in the Figures 1 and 3 are alike, and may or may not be provided with the flat portion 22.

The manner of making the swab 40, shown complete in Figures 3 and 5, is shown in detail in one way, in Figures 7, 8, 9 and 10, and is shown made in another way in Figures 11, 12 and 13. Let us consider first the formation of the mop made in accordance with the lay-out shown in Figures 7, 8 and 9, involving the folding together of the sides along a line which becomes a side edge of a completed swab. Starting with a sheet 40^a, of a given material, from which the swab is to be made, as shown in Figure 8, certain parallel line markings, made by pencil, ink or colored threads, serve to guide the operator. These line markings are numbered 61, 62, 63, 64, 65, 66, 67, 68 and 69. The line 65 is the partly cut dividing line, between the halves 70 and 71, from which are formed the two sides of the swab, bent along the uncut part of the line 65, when brought together. The lines 63 and 61, are the respective center lines of the halves 70 and 71. The top part of the sheet 40^a is cut on line 65, between the points 72 and 73, and for part 71, is cut along the diagonal lines 74 and 75. Below, the sheet 40^a is cut along the line 63, (for part 70), between the points 76 and 77, and is cut across on the short line 78. The sheet 40^a is also cut on the line 67 between the points 79 and 80, for the part 71, and is also cut across on the short line 78^a. Thus are formed the small turn-over flaps 81 and 82, in the half 70, and the small turn-over flaps 83 and 84, in the half 71. In Figure 9, the flaps 81 and 82 are shown turned back and sewed down, leaving a space 85 between them, within the half 70; while the flaps 83 and 84, of the half 71, are turned back and sewed down, leaving a space 86, between them. The triangular portions 81 and 88, of the half 70, are turned over on the respective diagonal lines 89 and 90, and are sewed down, forming a pointed end 91. The marginal sides 92 and 93 are turned inward and sewed over on the body of the material, and the marginal diagonal portions 94 and 95, are turned over on the respective diagonal lines 96 and 97, and are sewed down. The parts of the lower marginal portion 98, are turned up and sewed on to form a hem. Let us now consider the attached sleeve, shown in Figure 9, in its two parts 99 and 100, sewed at 101 and 102, to the respective swab halves 70 and 71. Each half of the sleeve is preferably formed double, with its edges turned in, as shown in Figure 10. The edges are afterward sewed together,

so that each sleeve half becomes a double thick, flat piece. We are now ready to turn the halves 70 and 71, with their respective sleeve halves 99 and 100, attached. Figure 7 shows the halves 70 and 71, nearly folded together along the line 65, which becomes a side edge of the swab when it is complete. When the halves 70 and 71 are brought together, the contiguous parts are sewed along the lines 103, 104, 105, 106, 107, 108, 109 and 110, leaving the flaps 31 and 32 free, to be releasably fastened together by the snap fasteners 35, and the tapes 36.

Considering the formation of the swab made in accordance with the lay-out shown in Figures 11, 12 and 13, the arrangement of the parts is such as to have the line, upon which the two halves are folded together become the bottom edge of the completed swab. As shown in Figure 11, a piece 111, of a strip, of cotton or other suitable sheet material, with selvages 112, is used, so that a strip of cloth, of the width that the swab is to be, can be selected and thus avoid turning over the side edges. Certain lines are drawn upon the surface of the cloth piece 111, which is of a length equal to twice the length the swab is to be. A center line 113, parallel to the edges 112, of the piece, is drawn with two spaced parallel lines 114 and 115, to indicate the spacing of a center opening, in the swab, to receive such a sleeve portion as is shown in Figure 10. A cross-line 116 is drawn half way between the ends of the piece 111, to designate the bend, when the two halves 117 and 118, of the swab, are brought together, so that the cross-line 116 is at the bottom edge of the swab. The piece 111 is cut on the diagonal lines 119 and 120, at one end, and on lines 121 and 122, at the other end. The piece 111 is also cut intermediate of its ends, on the full cross lines 123 and 124, and on the full part 125, of the center line 113, forming the flaps 126 and 127, which are turned back and are sewed down to create an opening between the lines 114 and 115, to receive parts 128 and 129, which, when sewed together form the attached sleeve portion, of the swab. The diagonal lines 121 and 122, of the portions 130 and 131, are their cut edges and these portions 130 and 131 are folded over on the lines 132 and 133, respectively, and are sewed down on the body of the swab to form the pointed end of the swab half 118. The outer end of the swab half 117 is bound over with suitable tape 134, and when the two halves 117 and 118 are folded together, on the cross-line 116, the point 135, of the half 118, comes to the portion 136, of the tape 134, so that the portions 130 and 131 will come below 117.

A partial folding of the halves 117 and 118, is shown in Figure 13, where snap fasteners 137, and tapes 138, are attached to the swab, at its closing edges. When the two halves 117 and 118, of the swab shown in Figure 13, are brought together, the outer edges of the two halves are sewed together all around, except at the diagonal edges of the ends, which are left free to form flaps, similar to the flaps 31 and 32, shown in Figure 7.

Where a selvaged strip of material, as 111, is used, of the appropriate width, a saving of time and material is to be had over using cloth of a width necessitated by the lay-out above described, in connection with Figures 8 and 9.

The spacing of the rearwardly extending frame portions 26 and 27 is made ample, so that, when the swab is fully on the frame and the sleeve 75,

covers the joint, between the handle and the frame, as well as extending part way along the handle, there will be afforded freedom of angular action, of the frame and swab either way, with 5 respect to the handle. By pivoting the handle at a mid-point in the body of the frame, there is afforded a better balancing of the frame on the handle, to facilitate the practical handling of the mop in use, as well as affording an opportunity 10 to work the mop on the floor, around legs of tables, by having the spaced frame portions straddle the point of contact of the furniture leg with the floor.

In Figure 1, the swab 28 is shown drawn part 15 way up on to the frame, with the spaced extended portions entered part way into the respective pockets 29 and 30. The sleeve 37, shown covering the handle end and cap 16, is, in this case, separate from the swab 28, and is adapted to be 20 used with any kind of a swab, other than the swab 28, which is adapted to fit a frame attached to a mop handle, and serves to cover the handle end and joint to prevent marring any object the handle end joint may otherwise come in contact 25 with.

The swab shown in Figures 3 and 5 has the sleeve 39 made integral with the body of the swab, and, as shown in Figure 5, where the sleeve 39 bends on the swab body as the handle is held 30 at a working angle with the floor 111^a, the swab 40 is held from slipping back off the mop frame 18. This tends to also relieve the strain on the overlapped marginal portions 33 and 34, as well as their snap fasteners 35 and bow knots at 36^a. 35 The method of making the swab 40 above described and illustrated in Figures 7, 8 and 9, in connection with one lay-out, is such as to facilitate the manufacture of the swabs, the operator being particularly guided by the parallel 40 lines 61, 62, 63, 64, 65, 66, 67, 68 and 69, which may be pencil or crayon lines or colored threads woven into the fabric, of the sheet material used. The method of making the swab 40 in connection 45 with the lay-out described and shown in Figures 15, 16 and 17, involves the use of a selvaged strip, and as explained above, is designed to save both time and material over the lay-out and construction shown in Figures 7, 8 and 9.

The mop is designed to be reversible, one side 50 can be used for dusting, while the other side can be used for polishing. The swab 28, adapted to fit the frame 18, may be made having both sides alike, as both sides made of sheepskin, with a wool surface, for polishing, or both sides may be 55 of fabric and yarn adapted for dusting.

I claim:

1. In a mop having a mop handle, a swab frame pivotally mounted mid-way between its ends on said handle and having two spaced arm portions positioned to have said handle swing between them in angular relation, a swab adapted to fit over and cover said frame, said swab including, at one end, two pocket portions, adapted to fit over the arm portions of said frame, two flap portions to said swab, at the opposite end of said swab to the pocket portions, each flap portion extending substantially across the width of the swab, a sleeve portion to said swab between said pocket portions fitting around said handle, and means for securing said flaps together at their free end edges; said swab being adapted to be slipped upon said frame in the following manner: first passing said handle into said sleeve and drawing said swab up onto said frame, to have the said arm portions, of said frame, engage said 20 pockets, and subsequently joining said flap ends together, over that edge of said frame, which is opposite said arm portions.

2. A mop swab for fitting over a mop frame and handle pivoted thereto at its mid-portion, 25 where the frame has two spaced arm portions adapted to pass said handle, when swinging thereon, said swab comprising two flat sides, partly joined together at their edges and forming, two spaced pocket portions, at one end of said 30 swab, said swab including a sleeve for covering the pivotal connection of said handle to said frame, said pocket portions being adapted to fit over said arm portions, respectively, a flap portion to said swab, included in each of said flat 35 sides, positioned at the opposite end of the swab to said pocket portions, and means for joining the free edges of said flat portions, over the edge of the frame, opposite said arm portions.

3. In a mop having a mop handle, a swab frame 40 pivotally mounted mid-way between its ends on said handle and having two spaced arm portions positioned to have said handle swing between them in angular relation, a swab fitting over and covering said frame, said swab including, at one end, two pocket portions, adapted to fit over the arm portions of said frame, two flap portions to said swab, at the opposite end of said swab to the pocket portions, each flap portion extending substantially across the width of the swab, a 50 sleeve fitting over said handle and over the pivotal connection between the handle and the frame, and means for securing said flaps together at their free end edges.

MAX VEECK. 55
